(57) **CLAIM**

The ornamental design for a light fixture, as shown and described.

DESCRIPTION

This application is related to commonly assigned, concurrently filed application Ser. No. 29/269,139, the disclosure of which is hereby incorporated by reference herein.

FIG. 1 is an isometric view from above of the light fixture of the present invention;

FIG. 2 is an isometric view from below thereof;

FIG. 3 is a top plan view thereof;

FIG. 4 is a left-side elevation view thereof;

FIG. 5 is a right-side elevation view thereof;

FIG. 6 is a front elevation view thereof;

FIG. 7 is a rear elevation view thereof;

FIG. 8 is a bottom plan view thereof;

FIG. 9 is the same view as FIG. 1 without any environmental structure; and,

FIG. 10 is the same view as FIG. 2 without any environmental structure.

The broken line showing is for illustrative purposes only and forms no part of the claimed invention.
